CLAIM

I claim the ornamental design for the dual CD continuous play player, as shown in the accompanying figures.

DESCRIPTION

FIG. 1 is a front perspective view of the dual CD continuous play player of the present invention.

FIG. 2 is a side elevational view of the dual CD continuous play player of the present invention.

FIG. 3 is a front perspective view of an additional alternative embodiment of the dual CD continuous play player of the present invention.

FIG. 4 is a side elevational view of the dual CD continuous play player of FIG. 3.

FIG. 5 is a front perspective view of an additional alternative embodiment of the dual CD continuous play player of the present invention; and,

FIG. 6 is a side elevational view of the dual CD continuous play player of FIG. 5.
